UNITED STATES PATENT OFFICE.

ROBERT W. EDENS AND SIMON EDWARD CLEVER, OF FULLERTON, CALIFORNIA.

APPARATUS FOR SEPARATING CEMENTED WELL CASINGS.

1,427,524.

Specification of Letters Patent. Patented Aug. 29, 1922.

Application filed September 7, 1920. Serial No. 408,601.

To all whom it may concern:

Be it known that we, ROBERT W. EDENS and SIMON EDWARD CLEVER, citizens of the United States, residing at Fullerton, in the county of Orange and State of California, have invented a new and useful Apparatus for Separating Cemented Well Casings, of which the following is a specification.

This invention relates to an apparatus for separating cemented well casings and has for its object to provide a means by which said casings may be separated without injury thereto so that they may be subsequently utilized.

Another object is to provide an apparatus for separating cemented well casings which consists of boring the cement from between the walls of the casings.

Another object is to provide a rotatable tubular boring tool longitudinally fed between the casings in a boring operation, and to provide means for automatically arresting said longitudinal feed.

Another object is to provide a quick return for the tool and to provide means for lubricating the cutting edge thereof and to flush the borings from the casing.

Various other objects and advantages will be more fully apparent from the following description of the accompanying drawings, which form a part of this disclosure, and which illustrate a preferred form of embodiment of the invention.

Of the drawings:

Figure 1 is a top plan view of the apparatus.

Figure 2 is an enlarged section on line x^2-x^2 of Fig. 1.

Figure 3 is a longitudinal central vertical section on line x^3-x^3 of Fig. 1.

Figure 4 is a detail section on line x^4-x^4 of Fig. 3.

Figure 5 is a plan section on line x^5-x^5 of Fig. 4.

Figure 6 is an enlarged detail section on line x^6-x^6 of Fig. 3.

Figure 7 is an elevation of the rear end of the apparatus.

Figure 8 is a transverse section on line x^8-x^8 of Fig. 1.

Figure 9 is a section on line x^9-x^9 of Fig. 1.

Figure 10 is a transverse section on line $x^{10}-x^{10}$ of Fig. 1.

Figure 11 is a section on line $x^{11}-x^{11}$ of Fig. 1.

Figure 12 is a vertical section on line $x^{12}-x^{12}$ of Fig. 3; and

Figure 13 is an enlarged fragmentary section of a detachable cutting sleeve for the tool.

In the drilling of oil wells water strata are quite frequently encountered and as the laws governing the drilling of oil wells require that these water strata be blocked off before drilling is continued it becomes necessary to cement the well.

The usual method of cementing a well is to drive the outer casing, for instance a twelve inch casing, part way through the water strata and then insert a smaller casing, say a ten inch casing, inside the outer casing, and also driving said inner casing part way through the water strata. A mixture of cement is then forced down the inner casing, and laterally into the water strata and upwardly between the two casings cementing the casings together and forming a substantial block of cement in the water strata. After this cement is hardened the drilling of the well may be continued through the inner casing, the water strata having been completely blocked off.

After these cemented casings have been withdrawn from a well they are of no further use unless separated and as such casings are of considerable value it will be evident that a method by which they can be separated without injury is very desirable.

The herein described apparatus accomplished this result for the first time in a manner which leaves the casings in as perfect a condition as before separation, and which is entirely within reasonable cost limits.

Other methods which may suggest themselves, such as the utilization of acids or of heat to disintegrate the cement, are obviously impractical as the action of these elements are detrimental to the casings and would leave them unfit for immediate use.

In general terms, the apparatus illustrated in the drawings provides a tubular boring tool A having a toothed forward end and rotatably journaled at its rear end in a longitudinally slidably tool carriage B which is translated, by suitable mechanism, along parallel tracks C-C which are a part of the stationary framework of the machine. Gear connections between the tool chuck and a constantly rotating shaft D provides a rotary drive for the tool and there is pro-

vided a stop mechanism to stop the feed of the tool at a predetermined point in its forward travel and other devices providing a quick return feed, and to provide for 5 training lubricating and flushing fluid to the working end of the tool.

Describing more in detail, the framework of the apparatus comprises a forward transverse frame structure E which provides a 10 support for the forward ends of the tool A and the shaft D, a rear transverse frame structure F supporting the drive and control mechanism, and an intermediate frame structure G supporting a main drive shaft H. 15 These frame structures are preferably formed of standard angle iron and suitable reinforcing plates and are adapted to rest on suitable base beams or on a floor. The forward frame structure E provides four vertical legs 1, a table plate 2 supported on transverse angle beams 3, opposed transverse angle beams 4 joined to legs 1 below the table plate, and horizontal bearing supporting plates 5 joined to the beams 4. The intermediate frame structure G provides four vertical legs 6 and two shorter legs 7, the legs being joined together and maintained rigidly in spaced relation by transverse angle beams 8 and horizontal bearing supporting plates 30 9—10—11 connecting said beams. The rear frame structure F likewise provides four vertical legs 12, table plates 13—14 supported on transverse angle beams 15, opposed angle beams 16 joined to the legs 12 below the table 35 plates, and horizontal bearing supporting plates 17—18—19—20 joined to the beams 16.

The parallel tracks C—C are respectively positioned on opposite sides of the longitudinal center of the machine and are supported upon the upper ends of the vertical legs 1—6—12 of the frame structures E—G and F respectively. Each track consists of an angle beam 21 supporting three superposed plates having finished surfaces (see 45 Fig. 2) the center plate 22 being narrower than the adjacent plates 23—23, providing an intermediate groove 24. In securing the plates to the angle beams 21, the plate 22 is first riveted to the lower plate 23 and said 50 lower plate 23 is then riveted to the beam 21, the upper plate being then attached by bolts so that it may be removed if necessary.

The tool carriage B comprises a main body 25 having secured at opposite sides thereof, laterally projecting horizontal plates 26—each plate engaging within a respective groove 24 of the parallel tracks C in abutting engagement with the narrow plate 22 thereof which serves as the base of the groove and 60 maintains the carriage against transverse movement. The upper surface of the body 25 is formed to provide a lower half-bearing 27 receiving a chuck body 28 which has formed on its forward end a chuck gear 29 65 and on its rear end a flange 30. An upper

half-bearing cap 31 is secured on the body 25, the flange 30 engages the body and cap to retain the chuck against forward movement relative to the carriage and the face of the gear 29 prevents a rearward movement of 70 the chuck in the carriage by engaging against a thrust washer 32 which in turn engages the body 25 and cap 31. The inner wall of the chuck body 28 has a tapered portion 33 with which cooperates a pair of semi-circular chuck jaws 34 having similarly tapered peripheral surfaces and radially projecting annular flanges 35. Said flanges have series of elongated radial slots to receive companion bolts 36 projecting longitudinally 75 from the face of the chuck gear 29 and engaged by clamp nuts 37 operable to translate the chuck jaws to clampingly grip the tool A. This mechanism provides a cone chuck rotatably journaled in the carriage and retained against longitudinal movement relative thereto and it also provides a chuck adapted to grip tools of different diameters. If it is desired to use a tool smaller than the minimum clamping limit of a certain set of 80 chuck jaws said set can be removed and another set of smaller internal bore can be substituted.

The forward end of the tool is supported upon a pair of longitudinally disposed rollers 38 journaled in journal boxes 39 which are secured upon the table plate 2 of the frame structure E and has its forward edge cut to provide cutting teeth e. 95

The shaft D from which motion is derived 100 for rotating the tool, is journaled in journal boxes 40—41 secured respectively on the table plates 2 and 13 of the frame structures E and F, and has a longitudinal key 105 way d. A gear pinion 42 meshes with the chuck gear 29 and is splined to the shaft D to rotate therewith and to slide longitudinally thereof, the pinion 42 being journaled in a lower half-bearing 43 in the carriage body 25 and in a bearing cap 44 secured thereto 110 and retained against endwise movement within said bearing by a flange 45 and the toothed portion of the pinion.

A beveled pinion 47 secured to the rear 115 end of the shaft D meshes with a companion beveled pinion 48 secured to one end of a transmission shaft 49, said shaft 49 being journaled in journal boxes 50—51 secured upon the table plates 13—14 respectively of the rear frame structure F. A belt pulley 52 is secured to the outer end of the shaft 49 120 and connects by a belt 53 with a pulley 54 on the main drive shaft H to complete the tool drive.

Before describing the carriage feed it will 125 be stated that the main drive shaft H is journaled in journal boxes 55—56—57 secured upon the plates 9—10—11 respectively, of the intermediate frame structure G, and has fixed thereto the pulley 54, pulleys 58 and 130

59 and a main drive pulley 60 which is in driving connection with any suitable source of power, such as an electric motor or a gas or oil engine.

5 Positioned below the table plates of the rear frame structure F is a differential drive mechanism which comprises opposed horizontally aligned shafts 62—63, the shaft 62 being journaled in journal boxes 64—65 10 mounted respectively on the plates 17—18, and the shaft 63 being journaled in journal boxes 66—67 mounted respectively on the plates 19—20. The shaft 62 has fixed to its outer end a belt pulley 68 and the shaft 63 carries at its outer end a fixed pulley 69 secured to the shaft and a loose pulley 70 rotatable thereon. The differential gear mechanism operatively connecting the inner ends of the shafts 62—63 is illustrated in 15 detail in Fig. 6, and comprises beveled pinions 71—72 keyed respectively to the inner ends of the shafts and a plurality of floating beveled pinions 73 meshing with the pinions 71—72, the pinions being enclosed within a gear housing which comprises opposed sections 74—75 loosely journaled upon the hubs of the pinions 71—72 and an intermediate annular chain wheel or sprocket rim 76 all bolted together by bolts 20 77 to form an integral housing and constituting the intermediate member of the differential mechanism. Any desired number of the gears 73 may be provided and mounted for independent rotation within 25 the housing, in the drawings, two being shown, each loosely journaled upon opposite ends of a transverse stud shaft 78 carried by the housing.

Referring particularly to Figs. 3—4—9, 30 80 designates a chain wheel or sprocket mounted upon a shaft 81 journaled in opposed journal boxes 82 supported upon the plates 5 of the forward frame structure E, and 83 designates a lug projecting downwardly from the tool carriage body 25. Pivoted on said lug is a link member 85 to the opposite ends of which are connected the terminal ends of a feed chain 86. The chain is rove around the chain wheel rim 76 of the 35 differential housing and extends forwardly and is rove around the chain wheel 80.

The belt pulley 69 of the differential shaft 63 is driven by a belt 88 connecting with the wide face pulley 58 on the main drive shaft 5 H and the belt pulley 68 of the differential shaft 62 is driven in reverse direction by a belt 89 which connects with the pulley 59 on said main drive shaft, the runs of the belt 89 being crossed as indicated in Fig. 1. 60 It will, of course, be understood that if the two differential shafts 62—63 are driven in opposite directions at equal speeds, there will be no rotation of the chain wheel 76, therefore, in the present device the pulley 69 65 is of slightly less diameter than is the pulley

68, giving a very slow rotation to said chain wheel in the direction indicated by the arrow in Fig. 3, for a forward feed of the tool carriage B. It is, of course, obvious that instead of the pulley 69 being smaller 70 than the pulley 68, these pulleys may be of equal diameter and the main shaft pulley 58—59 may be of different relative diameters.

It is desirable that the tool carriage be 75 stopped at predetermined points in its forward travel and for this purpose there is provided an automatic belt shifting device associated with the pulleys 69—70, said device comprising a square rod 90, (see Figs. 80 3—10—12), which is slidably mounted in brackets 91—92 attached to the forward legs 12 of the rear frame structure F and in a bracket 93 attached to a plate 94 as a part of said structure and having an aperture 85 through which the lower run of the chain passes, the rod 90 having upwardly projecting fingers 95 secured to its outer end and spaced apart to engage the opposite edges of the belt 88. A spring 96 surrounding the 90 rod 90 between the bracket 92 and the inner finger 95 and exerts its tension to translate the rod outwardly to shift the belt 88 to the loose pulley 70 when the rod is released. To throw in the carriage feed the rod 90 is 95 translated inwardly and latched in inner position until automatically released, the means provided for translating the rod 90 inwardly consisting of a hand lever 97 attached to a rock shaft 98 which is journaled 100 in bearings 99 in the frame structure and has attached to its inner end an arm 100 engaging a transverse pin 101 projecting laterally from the rod, and the means for latching the rod in inner position consisting 105 of a latch 102 pivoted on the bracket 93, a spring 103 tending to maintain the lower end of said latch in engagement within a notch 90^a cut in the side of the rod 90, when the rod is in inner position. The upper end 110 of the latch 102 is bifurcated to extend on opposite sides of the feed chain 86 and there is provided a trip block 104 which is adapted to be removably attached to the lower run of the chain 86 in a position relatively 115 coincident to the selective length of feed to be imparted to the tool carriage. Said trip block preferably has a medial orifice through which the chain passes and a transverse pin 105 which passes through a link 120 of the chain to maintain the block in set position.

In throwing in the carriage feed, the hand lever 97 rocks the shaft 98 to translate the rod 90 inwardly and shifts the belt 125 88 to engage and drive the belt pulley 69, and the latch 102 engaging into the notch in the rod maintains said rod in inner position. The trip block 104 being previously set in accordance with the desired length 130

of carriage feed, will travel rearwardly as the carriage is fed forwardly and upon reaching the latch will engage its upper bifurcated end and disengage its lower end 5 from the notch in the belt shift rod 90, whereupon, the spring 96 automatically translates the rod outwardly and shifts the belt 88 to the loose pulley 70. When the belt 88 is so shifted the differential shaft 63 and 10 connected parts become idling elements and no further rotative motion will be transmitted to the chain wheel 76. This mechanism provides automatic stop means for disabling the carriage feed at selective points in the 15 forward travel of the carriage and means for manually throwing in the carriage feed and conditioning the stop for subsequent operation.

To provide for a quick return travel of the 20 tool carriage I provide a manually operated brake means for gripping the differential shaft 63 to hold the differential pinion 72 stationary so that the pinion 71 will drive the pinions 73 around said stationary pinion 25 72, carrying with them the differential housing and chain wheel 76 in reverse rotation at an increased speed. Said brake mechanism comprises a brake drum 110 secured to the shaft 63 and engaged by a brake 30 band 111 extending around said drum and actuated by a brake lever 112, the brake lever being pivoted at 113 on the frame structure F and the brake band being attached at one 35 end to the lower end of said lever and at the other end of the pivot stud 113 or to the frame, a spring 114 normally maintaining said lever in releasing position. When the outer end of the lever 112 is depressed the 40 brake band 111 will grip the periphery of the brake drum and hold the shaft 63 and connected parts stationary providing a quick return carriage drive as above explained.

The boring tool A may be formed of a 45 length of well casing one end of which is notched to provide the teeth e, or if desired the casing may be threaded and a steel shoe 115 screwed thereon, said shoe having teeth 116 cut in its outer edge. (See Fig. 13).

To provide for entraining lubricating and 50 flushing fluid, such as water, to the cutting zone, a conduit 117 is mounted upon the carriage and extends into the rear end of the tool, the opposite end being connected by a flexible conduit 118 with a source of supply. To prevent said fluid flowing out the 55 rear end of the tool there is provided a bushing forced into the end of the tool and having a medial orifice through which the fluid conduit 117 projects. (See Fig. 5). If 60 desired this bushing may be eliminated if the apparatus is mounted in a slightly forwardly inclined plane tending to direct the flow of fluid forwardly to the cutting end of the tool.

65 In operation, with the cemented casing

secured in a suitable vice or like structure and positioned in axial alignment with the boring tool, the rotation of the main drive shaft H will cause the tool A to be driven by the belt 53 shaft 49 and shaft D and the belt 89 will rotate the differential shaft 62 on the one side, the opposite differential shaft 63 idling without causing a rotation of the carriage feed chain wheel 76. The trip block 104 having been positioned on the chain 86 coincident to the desired length of the tool feed, the hand lever 97 is shifted to the left (Fig. 7) to translate the belt shift rod 90 inwardly to shift the belt 88 from the loose pulley 70 to the differential drive pulley 69 and when so shifted the notch in the rod 90 will be positioned in alignment with the trip latch 102 so that said latch will engage therein and maintain the rod in operated position against the tension of the spring 96. This shifting of the belt 88 results in both differential shafts 62-63 being driven in reverse directions at slightly varying speeds, producing a forward feed of the carriage and as said carriage travels 90 forwardly the trip block 104 is carried rearwardly so that upon reaching the trip latch 102 it will rock said latch out of engagement with the notch in the belt shift rod 90 and said rod will be shifted outwardly 95 by its spring 96 and stop the carriage feed as above explained. During the forward travel of the carriage the lubricating and flushing fluid will be turned on to lubricate the tool and flush away the borings. If 100 the operator now wishes to retract the tool he depresses the brake lever 112 to hold the differential shaft 63 against rotation to provide a quick return of the carriage as previously explained.

105 We claim:

1. An apparatus of the class described combining a frame, a tool carriage slidable on the frame, a tubular tool rotatable on the carriage, means for rotating the tool, means for translating the carriage, and means associated with the carriage and adapted to render the carriage translating means ineffective when said carriage reaches the end of its operating stroke.

110 2. An apparatus of the class described combining a frame, a tool carriage slidable on the frame, a tubular tool rotatable on the carriage, means for rotating the tool, means for translating the carriage, selectively positioned means associated with the carriage and adapted to render the carriage translating means ineffective when said carriage reaches the end of its operating stroke, and means providing a quick return translation 115 of the carriage.

120 3. An apparatus of the class described combining a frame, a tool carriage slidable on the frame, a tool rotatable on the carriage, means for rotating the tool, a differ- 125

ential gear mechanism having opposed differential shafts and an intermediate cooperating member, means connecting said intermediate member to the carriage, means driving the differential shafts at relatively different speeds in opposite directions to rotate the intermediate member for translating the carriage.

4. An apparatus of the class described combining a frame, a tool carriage slideable on the frame, a tool rotatable on the carriage, means for rotating the tool, a differential gear mechanism having opposed differential shafts and an intermediate cooperating member, means connecting said intermediate member to the carriage, means driving the differential shafts at relatively different speeds in opposite directions to rotate the intermediate member for translating the carriage, and means functioning to disconnect the drive from one shaft to discontinue the rotation of the intermediate member.

5. An apparatus of the class described combining a frame, a tool carriage slideable on the frame, a tool rotatable on the carriage, means for rotating the tool, a differential gear mechanism having opposed differential shafts and an intermediate cooperating member, means connecting said intermediate member to the carriage, driving means for each shaft for driving said shafts at relatively different speeds in opposite directions to rotate the intermediate member, means for disconnecting the drive from one of the differential shafts permitting its idle rotation by the opposed shaft and discontinuing the rotation of the intermediate member, and means for arresting the idle rotation of the one shaft to cause a quick reverse rotation of the intermediate member.

6. An apparatus of the class described combining a frame, a tool carriage slideable on the frame, a tool rotatable on the carriage, means for rotating the tool, translating means for the carriage, a control device for the translating means manually operated to cause the transmitting means to translate the carriage in one direction and automatically normalized to render the transmitting means ineffective, retaining means releasably maintaining the control device in condition for automatic operation, and means associated with the carriage to trip the retaining means.

7. An apparatus of the class described combining a frame, a tool carriage slideable thereon, a tool rotatable on the carriage, means for rotating the tool, a differential gear mechanism having opposed differential shafts and an intermediate cooperating member, means connecting said intermediate member to the carriage, drive means for one shaft, drive means for the opposite shaft, said drive means rotating the shafts in op-

posite directions at relatively different speeds to rotate the intermediate member in one direction, means controlled by the movement of the carriage for disconnecting one drive means permitting its associated shaft to rotate idly and the intermediate member to remain stationary, and means for arresting the idle rotation of said shaft to cause a quick reverse rotation of the intermediate member.

8. An apparatus of the class described combining a frame, a tool carriage slideable thereon, a tool rotatable on the carriage, means for rotating the tool, a differential gear mechanism having opposed differential shafts and an intermediate cooperating member having a chain sprocket, a chain sprocket journaled at the forward end of the frame, a chain attached to the carriage and rove around both sprockets, and driving means for each shaft driving said shafts in opposite directions at relative different speeds to cause a rotation of the intermediate member.

9. An apparatus of the class described combining a frame, a tool carriage slideable thereon, a tool rotatable on the carriage, means for rotating the tool, a differential gear mechanism having opposed differential shafts and an intermediate cooperating member having a chain sprocket, a chain sprocket journaled at the forward end of the frame, a chain attached to the carriage and rove around both sprockets, driving means for each shaft driving said shafts in opposite directions at relative different speeds to cause a rotation of the intermediate member, and means for disconnecting one of said driving means to discontinue the rotation of the intermediate member.

10. An apparatus of the class described combining a frame, a tool carriage slideable thereon, a tool rotatable on the carriage, means for rotating the tool, a differential gear mechanism having opposed differential shafts and an intermediate cooperating member having a chain sprocket, a chain sprocket journaled at the forward end of the frame, a chain attached to the carriage and rove around both sprockets, driving means for each shaft driving said shafts in opposite directions at relative different speeds to cause a rotation of the intermediate member, means for disconnecting one of said driving means to permit its companion shaft to rotate idly and discontinue the rotation of the intermediate member, and means for arresting said idly rotating shaft to cause a reverse rotation of the intermediate member.

Signed at Fullerton, California, this 30 day of Aug., 1920.
